UNITED STATES PATENT OFFICE

172,314

CHILD'S PROTECTIVE MAT

Helen Ann Saidel, Chicago, Ill.

Application October 30, 1953, Serial No. 27,395

Term of patent 3½ years

(Cl. D92—21)

To all whom it may concern:

Be it known that I, Helen Ann Saidel, have invented a new, original, and ornamental Design for a Child's Protective Mat, of which the following is a specification, reference being had to the accompanying drawing, forming a part hereof.

The figure is a plan view of a child's protective mat, embodying my design.

The mat is of conventional thickness.

I claim:

The ornamental design for a child's protective mat, substantially as shown and described.
